LONG-LINE BRASSIERE

Alfred Egon Maas, New York, N.Y., assignor to Maidenform, Inc., New York, N.Y., a corporation of New York

Filed Dec. 7, 1964, Ser. No. 82,938

Term of patent 7 years

(Cl. D20—4)

The figure is a plan view of a long-line brassiere showing my new design, a portion of the bottom band at one end being broken away for convenience of illustration.

The characteristic of the design is in the prominently ribbed wide waistband in combination with the prominently ribbed narrower back bands.

I claim:

The ornamental design for a long-line brassiere, as shown and described.
